CONTOURED BOARD EGG CARTON

Richard F. Reifers, New Canaan, and William J. Hrozenchik, Stamford, Conn., assignors to Diamond International Corporation, a corporation of Delaware

Filed Sept. 13, 1961, Ser. No. 138,244
19 Claims. (Cl. 229—28)

The present invention relates generally to paperboard cartons, and more particularly to an improved one-piece, paperboard egg carton which is contoured to afford improved strength characteristics and increased egg-receiving space without departing from conventional exterior dimensions to permit the improved egg cartons to be accommodated in conventional packing cases.

Egg cartons of the character involved have generally been erected on automatic machinery, such as that shown, for example in United States Letters Patent to Jordan No. 2,700,922, issued February 1, 1955.

Egg cartons of the character involved have generally been constructed in the form of a rather narrow, hollow, rectangular box including two adjacent longitudinal rows of six egg-receiving cells. Many variations have been heretofore proposed in the art; however, the style generally identified as an "inverted V-bottom" wherein the longitudinal partition generally comprises an A-frame has generally been found to be an acceptable and satisfactory construction.

The prior art has indicated that the inverted V-bottom style or A-frame style egg carton generally requires a minimum of paperboard and thus, there has been a constant attempt in the prior art to improve this type of carton. A typical type of carton of the character involved is that disclosed in the United States Letters Patent to Reifers No. 2,873,059, issued February 10, 1959, and it will be observed that in this type of carton the longitudinal partition or A-frame does not extend through the entire depth of the carton.

Some of the requisites of egg cartons of the character involved are that they have (1) exceptional column strength, i.e., to resist impact or static loading on the upper surface of a packed egg carton; (2) have lateral compression resistance, i.e., to absorb impact or compression on the front and rear panels of the carton when packed with eggs; (3) have longitudinal compression resistance, i.e., to absorb and protect the contents against impact at one end or the other of the carton; (4) that the longitudinal partition be laterally stable to prevent the contents of a packed carton from rattling inside; (5) the carton can and must be readily stored in an unerected condition in order that a minimum amount of space will be required for packing during shipping and storage, prior to erection of the folded carton; (6) the carton should have diagonal twist stability, i.e., it should resist diagonal twisting when picked up on one side or the other; and finally (7) the carton should resist parallelogram-type of collapse under vertical loading, and in particular, the center partition should resist this type of collapse or movement inasmuch as once the center partition structure departs from its true longitudinal center, the structure would quickly lose its structural strength.

A primary object of the present invention is to provide an improved egg carton which includes all of the desirable requisites mentioned above, and which is constructed from a one-piece paperboard blank.

Another object of the present invention is to provide a novel egg carton of the character involved, which is constructed from a novel blank of paperboard or the like wherein the carton has an unusual capacity to receive eggs up to the maximum size involved, which is exceptionally

strong to absorb and protect the contents of a packed carton from lateral, longitudinal and vertical forces, which is readily erected, and which is practical and acceptable by the trade for the purpose intended.

Other objects and the nature and advantages of the instant invention will be apparent from the following description taken in conjunction with the accompanying drawings, wherein:

FIG. 1 is a plan view of a blank from which one embodiment of the novel egg carton of the invention is constructed;

FIG. 2 is an enlarged plan view of a portion of FIG. 1 showing the panel from which the transverse partitions are formed and the panels from which the longitudinal partition and bottom walls are formed;

FIG. 3 is a top plan view of the erected carton, with the cover removed;

FIG. 4 is a vertical section taken substantially on the plane of line 4—4 of FIG. 3;

FIG. 5 is a fragmentary perspective view of the erected carton, portions being broken away for purposes of clarity and showing interior structural details of the egg cells of the carton;

FIG. 6 is a side elevation of the erected carton shown in FIG. 3 with the cover attached;

FIG. 7 is a vertical section taken substantially on the plane of line 7—7 of FIG. 3;

FIG. 8 is a side elevation of the novel carton shown in its folded condition prior to the same being erected;

FIG. 9 is a plan view, similar to FIG. 2, and showing another embodiment of the novel carton;

FIG. 10 is a plan view, similar to FIG. 3, showing a portion of the carton erected from the blank of FIG. 9;

FIG. 11 is an end elevation looking from left to right at FIG. 10;

FIG. 12 is a diagrammatic force diagram illustrating the manner in which a vertical force to the lid of both of the embodiments of the carton will affect the longitudinal partition thereof;

FIG. 13 is an end elevation, similar to FIGS. 6 and 11, and showing a modified transverse partition;

FIG. 14 is an enlarged fragmentary view showing the details of the end cell transverse partition of the modified carton of FIG. 13;

FIG. 15 is a view similar to FIG. 13, showing another modified transverse partition for an end cell of the carton;

FIG. 16 is an enlarged view similar to FIG. 14 showing details of the transverse partition shown in FIG. 15;

FIG. 17 is a view similar to FIGS. 13 and 15 showing still another embodiment of a transverse partition for an end cell of an egg carton; and

FIG. 18 is an enlarged view similar to FIGS. 14 and 16 showing details of the transverse partition of FIG. 17.

While the egg carton of the invention is susceptible to numerous modifications, a considerable number of the exemplary embodiments shown and described have been made and used and have performed in an eminently satisfactory manner.

Referring to FIGS. 1 and 2, a blank from which one embodiment of the invention is produced is indicated generally at 10, the blank comprising a paperboard body member 12 including in the following order a glue flap 14, a transverse partition panel 16, a front wall panel 18, a first bottom panel 20, a pair of mirror-image longitudinal partition panels 22 and 24, a second bottom panel 26, a rear wall panel 28, a cover panel 30 and lock panel 32. The blank 10 includes longitudinal side margins 34 and 36 and a longitudinal, intermediate tear line 38 providing means whereby an erected carton may be separated to form two one-half dozen capacity cartons. The

two sides of the blank 10, as indicated at 40 and 42, are mirror images of each other, and thus, only one of these sides will be described in detail.

The glue flap panel 14 will be secured at a transverse glue strip 44 on the inner surface of the back wall panel 28. The lock panel 32 includes at its transverse marginal edge 46 a bayonet-type lock construction which is conventional.

The glue flap panel 14 is connected to the transverse partition panel 16 by fragmentary, scored hinge line segments 48-54. The transverse partition panel 16 is connected at its other transverse edge to the front wall panel 18 by means of similar fragmentary, scored hinge lines 48'-54'. The front wall panel 18 is connected to the first bottom panel 20 by means of a score line 56 interrupted by cuts 57. The interrupted score line 56 facilitates the erection of the carton and yet rigidifies the lower marginal edge at the base of the front wall of the erected carton. The first bottom panel 20 is connected to the first longitudinal partition panel 22 by fragmentary score or fold lines 58, 60, 62, 64 and 70. It will be noted that the fragmentary score line 64 is in angular relationship to the side edge 34 of the blank, and in the erected carton this construction will facilitate the contouring of a longitudinal partition of the erected carton; this construction to subsequently be described in detail. The first longitudinal partition panel 22 is connected to the second longitudinal partition panel 24 by means of perforated, interrupted score lines 72, 74 and 76. The second longitudinal partition panel 34 is connected to the second bottom panel 26 by fragmentary hinge lines 58', 60', 62', 64' and 70', which are substantially the same as the fragmentary score lines 58-70 previously described. The second bottom panel 26 is connected to the rear wall panel 28 by means of interrupted score lines 56' which serve to rigidify the lower edge of the carton at the base of the rear wall of the erected carton. The rear wall panel 28 is connected to the top or cover panel 30 by means of a transverse score line 78, and the cover panel 30 is connected to the lock flap panel 32 by means of a score line 80.

The glue flap panel 14, front wall panel 18, rear wall panel 28, cover panel 30, and lock flap panel 32 are substantially conventional, and thus, attention is drawn to FIG. 2, wherein the detailed structure of the novel egg carton is illustrated on a larger scale.

The transverse partition panel 16 comprises a pair of inwardly directed full cell partitions 80 and 82 and intermediate half cell partitions 84 and 86 disposed at one side of the tear line 38 which provides the sections 40 and 42. The full cell partition 80 is hingedly connected at the inner end of the fold lines 48, 48' by outwardly directed fold lines 88 and 90, respectively. When the full cell partition 80, as well as the full cell partition 82, are disposed in the condition shown in FIG. 3, i.e., when the carton is erected, the fold lines 88 and 90 tend to direct the full end cell partitions 80 and 82 outwardly for the purpose of providing maximum capacity for the end egg cells being formed.

The side margins of the partition 80, as indicated at 92 and 94, angle inwardly slightly; however, these side margins will substantially abut the respective inner surfaces of the front and back walls 20 and 26 of the erected carton as seen, for example, in FIGS. 6 and 11. The side margins 92 angle inwardly at 96 and 98, respectively. The side margins continue in inwardly angled portions 96 and 98 which merge into bottom margins 100 and 102, respectively, which continue in upwardly angled portions 104 and 106, respectively, forming the upper margin of the half-cell partition panel 84. The margins 92-106 are formed by cut lines, and the angular margins 96, 98 form one side of horizontally disposed abutment portions 108 and 110, respectively, which are detachably engaged by the bayonet lock portion 46 of the lock panel 32. The margins 104 and 106 continue in inwardly angled

margin portions 112 and 114, respectively, which terminate in outwardly extending collinear margins 116 and 118 which intersect converging margins 120 and 122 which are connected by a transverse margin 124. The portions 112-118 form locking noses 126 and 128 which will locking engage lower portions of the longitudinal partition of the erected carton.

It will be noted that the cut-lines or margins 104 and 106 are connected by a transverse margin 129 defining an upwardly projecting separator element 131 in the erected carton. Additionally, the full-cell partition 82 is a mirror image of the full-cell partition 80 and this structure will likewise be described with primed reference numerals identical to those used with respect to the description of the full cell partition 80.

The upper margin of the full cell partition 80 includes at the terminal end of the angular fold lines 88 and 90 inwardly directed margins 130 and 132, respectively, which intersect collinear margins 134 and 136, respectively, the margins 134 and 136 respectively intersecting diverging outwardly extending margins 138 and 140 connected by a margin or edge 142 coinciding with the outer edge 34 of the blank. The half-cell partition 84 is connected by hinge lines 144, 146 to the portions 108 and 110, respectively, at one end of the hinge lines 50 and 50', respectively. The partition 84 includes side margins 143 and 150 which are substantially normal to the side margin 34 of the blank, and which will have a substantially flush engagement with the respective inner surfaces of the front wall panel 20 and rear wall panel 26 in the erected carton. The partition 84 includes a lower margin 152 formed by a transverse cut line which intersects at intermediate portions thereof converging margins 154 and 156 which intersect a transverse margin 158 and 160, respectively intersecting margins 162 and 164 extending into the intermediate fragmentary portion of a bottom edge 166 of the lower edge margin of the partition 84. The margins 162, 164 and 166 form a spacer tab 168 which will be disposed between opposed inner surface portions of the longitudinal partition of the carton when the same is erected.

The partition 84 includes intermediately thereof apertures 170 and 172 respectively including an elongated slot portion 174 and 176 which respectively cooperate with locking noses on the longitudinal partition of the erected carton to stabilize the same against lateral shifting with respect to the front and rear walls of an erected carton.

The half-cell partition 86 comprises a mirror image of a half-cell partition 84, and, accordingly, comprises identical structure as the half-cell partition 84, and this structure will be identified with identical primed reference characters used with respect to the half-cell partition 84 without further description of the various parts.

It will be noted that the portion 178 formed by the hinge lines 54', 90' is formed by a cut line 180 which coincides with the tear line 38, this construction facilitating separation of the sections 40 and 42 of the erected carton.

Further, the inwardly angled fold lines 90' and 88' will tend to hinge the end cell 82 outwardly to afford maximum capacity for the end cell formed by the partitions 86, 82.

As previously mentioned, the first bottom panel 20 is hingedly connected to the front wall panel 18 by means of the score line segments 56, a substantial portion of this structure being eliminated in FIG. 2 for purposes of illustration. Likewise, a second bottom panel 26 is hingedly connected by the fragmentary score lines 56' to the back wall panel 28, see FIG. 1, and this structure has also been eliminated from FIG. 2.

The bottom panel 20 includes at opposite ends relatively narrow connecting straps 182 and 184 which are connected to a longitudinal partition panel 22 by hinge lines 58, 70, respectively, and hinge line 56, previously mentioned. The straps 182 and 184 include inner margins 186 and 188 defined by a cut line, and a cut line extends from the inner end of the hinge lines 58 and 70, respec-

tively, as indicated at 190 and 192. The cut lines 186 and 188 respectively continue in reverse bend cuts 194, 196 to provide lock flaps 198 and 200 which will engage one side of the full cell partitions in the erected carton. The cuts forming the margins 190, 192 intersect marginal edges 202, 204 of depending feet formed at opposite ends of the longitudinal partition panel 22. The margins 202 and 204 continue in inwardly extending aligned cuts or marginal edges 206, 208 which are intersected by angular cuts 210, 212 terminating at the ends of the hinge lines 60 and 64, respectively. The cuts or margins 202, 206 and 210 form a support foot element 214 between the hinge lines 58 and 60. The margins or cuts 190, 202, 206 and 210 define a support foot 214 at the lower edge of the longitudinal partition panel 222. Likewise, the cuts or margins 192, 204, 208 and 212 define a support foot 216 also at the lower edge of the longitudinal partition panel 22 and is similar in construction to the previously mentioned support foot 214. Extending from the hinge lines 60 and 64 are cut lines 218, 220 which define side edges of intermediate support feet of the longitudinal partition panel 22, the cut lines 20 continuing in a transverse hat-shaped cut 222 and 224, respectively, which intersects diverging cut lines 226 and 228 extending from opposite ends of the hinge lines 62. The cut lines 218, 222 and 226 define the lower margin of a support foot 230 at the bottom edge of the longitudinal partition panel 22, and the cuts or margins 228, 224 and 220 define a second support foot 232 similar in construction to the support foot 230. The cut lines 218, 226 and 220, 228 are connected by an arcuate cut line 219 and 229, respectively. In the blank, the support feet 214, 230, 232 and 216 extend into the first bottom panel 20, and when the longitudinal partition panels 22, 24 are folded upwardly out of the plane shown in FIG. 2, the support feet will be disposed adjacent the support surface, see for examples FIGS. 5-7.

The sections of the first bottom panel 20 opposite the hinge lines 60, 62 and 64 define bottoms of three egg cells formed in the erected carton, and these portions have formed therein cruciform cushion cuts 234, 236 and 238.

The second bottom panel 26 has a construction similar to that described with respect to the first bottom panel 20 and, accordingly, the identical structure will be identified with primed reference numerals.

The longitudinal partition panels 22, 24 are connected by the fragmentary score-cut hinge lines 72, 74 and 76 which define the uppermost portion of the longitudinal partition in the erected carton. Further, the longitudinal partition panel 22 is connected to the bottom panel 20 by means of the hinge lines 58-70, and the longitudinal partition panel 24 is hingedly connected to the bottom panel 26 by the hinge lines 58'-70'.

The longitudinal partition panel 24 is a mirror image of the longitudinal partition panel 22 of the fragmentary score-cut or hinge lines 72, 74 and 76. The longitudinal partition panel 22 includes at the left end, as in FIG. 2, an inwardly extending angular cut 234 spaced from the hinge line 72 and intersected by a cut 236, parallel to the outer margin 34 of the blank. The cuts 234 and 236 form an elongated tab or abutment strap 238 which will be disposed adjacent the outer surface of the full cell transverse partition 80 in the erected carton. The margin 236 intersected by an inwardly extending cut-line 240 terminates in an arcuate cut line 242 which extends angularly at 244. The angular cut line 244 intersects a margin 246 which is parallel to the margins 34 and 236 but which is spaced from the margin 236 by the distance D, as clearly indicated in FIG. 2. This spacing facilitates the entry of the transverse partition panel 80 between the margins 236, 264 and permits some longitudinal movement of the full cell transverse partition 80 in the erected carton. The margin 264 continues in an inwardly extending angular margin 266 which terminates at the left hand end of the hinge line 72. The other end of the hinge line 72 terminates in a transverse cut 268 which defines the

terminal end of a cut 270 in linear alignment with the hinge line 72. The other end of the cut 270 has extending therefrom an outwardly extending angular margin 272 which continues downwardly at 274 to form an abutment nose 276 engageable with one side of the half cell transverse partition 84 in the erected carton. The margin 274 continues in an outwardly extending margin 278 intersected by a downwardly extending margin 280 connected to a C-shaped cut line 282 which is connected to a downwardly extending margin 284 terminating in a transverse cut 285 at an intermediate portion of the foot 230. The cut line 285 has extending therefrom in linear alignment with the cut line 284 a cut-score fold line 286 terminating at 288 in the upper portion of the hat-shaped margin 222 of the support foot 230. The cut score line 286 will facilitate the contouring of the support foot 230 so that it extends out of the normal plane of the longitudinal partition panels, as shown, for example, in FIG. 7.

Further, the cut lines 278-284 form a lock nose 288 which will be received in the slot portion 176 of the aperture 172 of the erected carton. This construction will aid to prevent lateral shifting of the longitudinal partition in the erected carton. Additionally, the cut lines 284, 285 will form abutment flaps 287 which will engage a transverse partition in a direction opposite that through which the lock nose 288 extends. This expedient will stabilize and tend to prevent longitudinal movement of the transverse partitions.

The cut line or margin 278 continues in a margin 290 intersecting the longitudinally extending cut line 292, terminating in a small transverse cut line 294 at one end of the hinge line 74. The longitudinal partition panel 22 has formed at one side of the hinge line 74 a contour cut line 296 and a cruciform cut line 298. The portions of the longitudinal partition panel 22 to the right of the contour cut line 296 and cruciform cut line 298 are mirror images of the left hand portion of the partition panel 22 just described in detail, and thus, further description is believed unnecessary. The structure of the longitudinal partition panel 22 appearing to the right of contour cut lines 296 and 298 will be described by means of primed reference characters similar to that structure used to describe the structure to the left of the contour cut lines 296, 298.

In alignment with the transverse cut line 294 and spaced therefrom and parallel to the contour cut line 296 are fragmentary score cut lines 300 and 302, and intermediate linearly aligned cut lines 304, 306 and 308. In alignment with the cut line 268, which is in alignment with the terminal end of the hinge line 60, are fragmentary score cut lines 310 and 312 and intermediate cut lines 314, 316 and 318. The score cut lines 310, 312 and cut lines 314-318 provide contour cuts for the end cells of the erected carton, as clearly seen in FIG. 5. Additionally, spaced from and parallel to the cut line 318 is a cut line 320 and cruciform cushion cut line 322. It will be noted, that although the portions to the left and right of the intermediate cut lines 296, 298 are described as being mirror images, this structure is not identical in view of the angular hinge line 64 as compared with the hinge line 60 which is substantially at right angles to the marginal edge of the blank.

The longitudinal partition panel 24 is a mirror image of the longitudinal partition panel 22 as previously described, and accordingly, to avoid repetition of description, the similar structure with the exception of the distance D or D' will be described with the same reference characters using a prefix letter "s."

The blank 10 is formed by die cutting and by means of conventional methods and in order to initially fold the carton to the position shown in FIG. 8, the glue flap 14 is secured to a glue strip 44 after the partition panel 16 and front wall panel 18 are folded as a unit and in the same plane along the interrupted score line 56. Addi-

tionally, the bottom panels 20, 26 and longitudinal partition panels 22, 24 are permitted to remain in the same plane and are folded along the fold line 56'. It will be noted that the partition panel 16 and front wall panel 18 will be disposed between the cover panel 30 and the coplanar panels 20-26, this providing a substantially three-ply folded carton permitting a plurality of the cartons to be packed in a conveniently sized packing case as is conventional and permits the folded cartons to be stacked and packed on their ends in the packing case during storage and transit. This folded condition of the unerected carton provides very desirable strength characteristics during shipping and storage whereby the folded cartons will not readily become damaged, warped or distorted.

The folded cartons shown in FIG. 8 will be inserted into an automatic erecting apparatus and will be fed one-by-one through the apparatus whereby the erected carton of FIGS. 3-7 will be afforded.

Referring to FIGS. 3-7, the reference characters utilized in the description of FIGS. 1 and 2 have been applied to the similar parts in these figures in order to show the manner in which the previously described structure is positioned in the erected carton.

The fold lines 58, 58' at the end of the blank are spaced a greater distance from the colinear score lines 72, 74 and 76 than the fold lines 70, 70'. When the carton is erected as seen in FIG. 3, the locking noses 126, 128 which engage beneath cut lines 190, 190' will draw the outer walls of the erected carton slightly toward each other as compared with the transverse center dimension of the carton, i.e., the outer walls of the carton will bow or converge slightly from the center toward the ends. This results in the fold lines 60, 60' converging toward the end of the carton to become a substantial mirror image of the converging fold lines 64, 64'.

The slight bowing of the carton walls and convergence of fold lines 60, 60', although not easily discernible in the erected carton, affords resistance to diagonal twisting and increased resistance to vertical loading.

Referring to FIG. 3, it will be noted that the transverse partitions 80 shown therein will be urged slightly outwardly toward the extremities of a six-cell section of the erected carton due to the angular fold lines 88, 90 and 88' and 90'. Further, the dimension D, as indicated in FIGS. 3 and 4, will permit slight lateral movement of the end wall partitions 80, 82. Additionally, as seen in FIG. 6, for example, the portions 238', s238' are angularly spaced apart and will provide a cushion to also receive the force of blows applied to the outer ends of the erected carton.

When the carton is erected, the longitudinal partition portion 400 forming cells 402 and 404 will be contoured or diverged toward the half cell partition 84. The divergence of the longitudinal partition portion 400 is initiated at the transverse cut line 268 and is permitted by the cut line 270. Further, the spacer tab 168 will be disposed between the inner surfaces of the crease lines 286, s286, and thus support feet 230, 230' will be spread apart to form an enlarged vertically extending column. Further, as most clearly seen in FIG. 4, for example, the portions 276, s276 extend beyond a plane extending through the fold lines 286, s286 and when engaging the transverse partition 84, will cause it to be bent over or biased out of its general plane in the manner clearly shown in FIGS. 3 and 4. In effect, the longitudinal partition portion 400 is partially contoured toward the center cells 406 and 408.

The longitudinal partition portion 410, see FIG. 3, is symmetrically contoured toward both the half cell partition 84 and 86. The lock noses 288, s288, see the blank in FIG. 2, for example, also extend to the left beyond the fold lines 286, s286 and these lock noses or abutment portions will extend into the slots 176, 174 of the apertures 172, 170, respectively, of the half cell transverse partition. The transverse partition 84 will be maintained

substantially vertical by the portions 276, 288, and s276, s288 and is retained against lateral shifting to a substantial degree by the interengagement of the portions 288, s288 in the slots 176, 174, and the portions 272, s272, etc. 5 will be prevented from coming together since the portions 276, 276', etc. will extend over or lip on the edges 104, 106, etc. directly above the slots 176, 176', etc. in which the lock noses 288, 288', etc. are engaged; see FIGS. 5 and 7, for example. The longitudinal partition portion 410 diverges from the transverse cut 294 and longitudinal cut 292. When a blow is received in the end of the erected carton, the diverging portions of the longitudinal partition portion 400 tend to spread apart on the transverse partition 84 and absorb the shock of the blow and thus protect the contents of the erected carton. Further, when a blow is received on the front or rear portion of the carton, the previously mentioned lock noses engaged in the slots in the transverse half cell partitions tend to prevent lateral collapsing of the erected carton. Still further, as will be explained in detail relative to FIG. 12, when the carton is closed and a blow is received on the upper surface of the partition panel, the spaced feet of the vertical columns of the longitudinal partition will tend to move inwardly as indicated by the dotted lines of FIG. 12 to form an extremely rigid shock resistant carton. The same condition occurs with respect to the diverging exaggerated columnar feet 32, seen in FIG. 3, formed due to the fold lines 286', s286', it being noted that the six-cell section shown in FIG. 3 is substantially symmetrical about the central portion of the center cells 406, 408. Likewise, the half cell partition 86 is biased inwardly as seen in FIG. 4 by the abutment portions 276', s276' and lock nose portions 288', s288', the latter respectively cooperating with the slots 176', 174', of the respective apertures 172', 170'.

Referring to FIG. 12, wherein the carton is shown diagrammatically in order to emphasize the manner in which the partition columns react to a downward force F, the carton is substantially rigid at its upper corners AB and lower corners CD. When a vertical force F is applied to the upper edge E of the longitudinal partition, panels P, P', which are hingedly connected at H, H', respectively, the bottom panels B, B' will tend to move downwardly and force the panels P, P' inwardly or toward each other to cause the support feet to move toward each other and rigidifying of the longitudinal partition when the same is subjected to such vertical force.

Referring to FIGS. 9-11, there is disclosed a modified embodiment of the novel carton, and in FIG. 9, a fragmentary portion of the modified blank is indicated generally at 500, this view being substantially the same as FIG. 2 which has been previously described.

In the modified embodiment of FIGS. 9-11, the transverse partition panel is indicated at 516, the first bottom wall panel is indicated generally at 520, the first longitudinal partition panel is indicated generally at 522, the second longitudinal partition panel is indicated generally at 524, and the second bottom wall panel is indicated generally at 526. In the modified embodiment, the longitudinal partition portions will have substantially the same contouring as that described in detail with respect to the embodiment of FIGS. 1-7. Further, the half cell partitions will be biased or deformed out of their general plane to afford lateral stability to the longitudinal partition due to rattling of eggs or the like, which are disposed in a packed, erected carton. Additionally, the vertical columns formed on the longitudinal partition panel will function in the same manner as those of the previously described embodiment. In view of this, it is not believed necessary to describe the similar structure and the similarly functioning portions of the embodiment of FIGS. 9-11.

Referring particularly to the half cell partition panels 584 and 586, formed from the partition panel 516, it will be noted that this embodiment incorporates substantially

C-shaped opposed pairs of cut lines 670, 672 and 670' and 672', which are comparable in function to the apertures 170, 172 and 170', 172', respectively. The structure formed by the cut lines 670, 672 and 670', 672' will cooperate with the abutment portions 788, 788' and 788', 788' on the longitudinal partition panels 522, 524, respectively. All the above-mentioned abutment portions will extend through the respective C-shaped cut portions 670, 672 and 670', 672' in opposed relation from the two end cells extending toward the center cell, this cooperation being the reverse of the previously described embodiment.

Referring to partition panel 516, it will be noted that the full cell partitions 580, 582 each includes an intermediate vertical score line 581, 583 and 585, in each of the cell wall forming segments, and a small intermediate vertical score line 589 and 561 is provided between the respective vertical score lines 581, 583. This structure will permit the end walls of the end cells of the erected carton to be biased outwardly as clearly seen in FIG. 10, for the purpose of increasing the cell capacity of the carton. Further, as seen in FIG. 10, the two center cells, when receiving relatively large eggs therein, will urge the half cell partitions 584, 586 away from each other, thus moving the locking noses 788, 788' and 788', 788' into firm locked engagement with the respective cooperating C-shaped cuts 670, 672 and 670', 672' of the partitions 584, 586, respectively.

The first bottom cell 520 includes a slightly modified end strap 682 which is slightly angular, as indicated at 683 for the purpose of accommodating the slightly contoured end wall full cell transverse partition 580 when it is contoured outwardly, as clearly seen in FIG. 10.

The second bottom wall panel 526 includes a connecting strap 682' which is similar in structure and function to that of the first bottom wall panel 520, including the angular portion 683' which cooperates with the vertical score line 583, as seen in FIG. 10. The bottom cell panels 520 and 526 each includes an abutment nose portion 680', 685', respectively, which will engage the inner surface of the full cell partition 580 adjacent the vertical score lines 581, 583, respectively, to urge the full cell partitions to the contoured condition shown in FIG. 10. The structure at the right hand side of the blank 500 and the carton erected therefrom, as seen in FIG. 10, is identical and a mirror image of the structure at the left hand side and, accordingly, further description is believed to be unnecessary.

The longitudinal partition panels 522, 524 do not include the clearance D disclosed in the embodiment of FIG. 1-7. It will be noted that the margins 766 and 776 terminate in an abutment nose portion 767 and 776' which extends beyond or to the left of the portion 736 and 736' of the modified blank. The abutment noses 767, 776' will tend to urge the full cell partition 580 to fold inwardly about the short vertical score line 589 as clearly seen in FIG. 10.

The erected carton formed from the modified blank of FIG. 9 and shown in detail in FIGS. 10 and 11, is affected by vertical forces in essentially the same manner as the embodiment of FIGS. 1 through 7, and thus the description with respect to the force diagram shown in FIG. 12 applies to the modified embodiment.

It will be noted that the transverse partition panel 516 includes angular hinge lines 588, 590 and 590' which tend to swing the full cell partitions 580 and 582 outwardly when the carton is erected.

It will be noted in FIGS. 6 and 11 in the end views of the erected cartons of each of the embodiments, that the straps 238', 238' and 738, 738' are disposed in spaced relation adjacent the outer surface of the full cell transverse partitions to provide a good broad base or cushion against shock applied to the ends of the erected cartons.

In this regard, attention is drawn to FIGS. 13 and 14, wherein each of the previously disclosed embodiments

5 may incorporate a transverse full cell 880 which includes a depending central spacer tab 881 which will depend between the longitudinal partition panels to urge them into and retain them in a fixed locking relationship with respect to the modified hooks 526 and 528 which have a slight radius to facilitate movement of the longitudinal partition panels thereover.

10 Considering FIGS. 15 and 16, a similarly modified full cell transverse partition 880' is disclosed to have a depending spreader tab 881' which serves to maintain the longitudinal partition panels in locked relationship over the modified lock noses 526' and 528' of the modified full cell transverse partitions.

15 Considering FIGS. 17 and 18, modified lock noses 926 and 928 are disclosed. In this embodiment, camming edges 929 and 930 are provided on the lock noses 926 and 928, respectively, for the purpose of facilitating locking of the longitudinal partition panels during erection of the cartons.

20 In both of the disclosed embodiments, inasmuch as the longitudinal partition of the erected carton is contoured, this construction tends to apply tension in the erected carton along the longitudinal partition and tends to bow the central portion of the front and rear vertical walls outwardly. This, in effect, tends to rigidify the erected carton and maintain the erected carton in its locked condition after erection.

25 Briefly in review, there has been afforded a novel blank and carton fully conforming with the objects and prerequisites of the art. The carton has increased strength, is shock resistant in all directions, takes full advantage of internal enclosed space for egg room, and is readily packed and stored.

30 It will be obvious to those skilled in the art that various changes may be made without departing from the spirit of the invention. Therefore the invention is not limited to what is shown in the drawings and described in the specification but only as indicated by the scope of the appended claims.

35 40 What is claimed is:

1. In a rectangular blank for a one-piece carton, including in order, a lock panel, cover panel, a back panel, a bottom panel, a pair of longitudinal partition panels, a second bottom panel, a front panel, a transverse partition panel, and a glue flap panel, hinge forming means connecting said panels, said longitudinal partition panels including support leg forming portions extending into said bottom panel, fold lines extending into said support-feet forming portions for providing a contour to said support legs in an erected carton, abutment nose portions substantially in alignment with said fold lines and overlying each other, said transverse partition panel including full end cell transverse partition panels and intermediate adjacent half cell partition panels, said half cell intermediate partition panels including a pair of intermediate aperture portions engageable with the abutment portions on the longitudinal partition panels in an erected carton whereby the half cell transverse partition panels are biased out of their general plane in an erected carton.

ly aligned cut lines spaced on opposite sides of the center pair of partition panel portions, said central partition portion including cut lines therein extending into opposite edges thereof and spaced from the adjacent edges of the two pairs of transverse partition panel portions at opposite sides of the central pair of longitudinal partition panel portions.

5. The blank structure of claim 1; said full cell transverse partition panels including intermediate mutually parallel fold lines on opposite sides of the longitudinal axis of the transverse partition panel, and an intermediate fragmentary fold line disposed substantially on a longitudinal axis of said full cell transverse partition panels.

6. The blank structure of claim 1; said full cell transverse partition panels including opposed spacer tabs extending toward the half cell transverse partition panels and disposed on the longitudinal axis of said transverse partition panel for maintaining the longitudinal partition panels in spaced relationship when the carton is erected.

7. A folding paperboard, one-piece cellular, set-up carton of the type comprising a front side, a back side, a cover, bottom panels, a series of discrete and separate upstanding posts engageable at the upper ends thereof with an undersurface portion of said cover and each post comprising a pair of downwardly diverging panels extending from an upper, common straight fold line and forming longitudinal partition structure connected by said bottom panels to said front and back sides respectively, said discrete posts being separated from each other by upwardly opening vertical slots and transverse partition panels extending from said front to said back side through said upwardly opening vertical slots, characterized in that the tops of said discrete posts include an edge of said common fold line and at least one pair of upper, free marginal edges of said downwardly diverging panels, said upper free marginal edges having one end of each edge adjacent one end of said common fold line and the opposite ends of said free marginal edges being spread apart, said edge of said common fold line and said free marginal edges being substantially in the same plane.

8. A foldable, one-piece cellular set-up egg carton comprising front and back sides, a cover connected to one of said sides, bottom panels connected to said sides, a series of discrete and separate upstanding, column-like posts formed by longitudinally spaced vertical slots in a pair of downwardly diverging, longitudinal partition panels connected by said bottom panels to said front and back sides, said longitudinal partition panels including a common, longitudinal upper linear fold line through which said vertical slots open, and transverse partition panels connected to said front and back sides and extending through said vertical slots, said column-like discrete posts being engageable at said upper linear fold line with an undersurface portion of said cover, said posts including free upper margins diverging from said common fold line and opening toward said vertical slots and being disposed in a horizontal plane substantially coplanar with said common fold line and engageable with the undersurface portion of said cover laterally of the portions engaged by said common, linear fold line.

9. The structure of claim 8 in which said discrete posts include panel portions depending below said free upper margins and disposed outwardly beyond planes substantially coinciding with said downwardly diverging longitudinal partition panels.

10. The structure of claim 9 in which said discrete posts include depending foot portions terminating below an innermost portion of said bottom panels.

11. The structure of claim 10 in which said foot portions include an intermediate fold line depending from said upwardly opening vertical slots for providing a contour to said foot portions.

12. The structure of claim 8 in which said front and back sides converge toward each other from a central portion of said carton.

13. The structure of claim 9 in which said transverse partition panels include transverse apertures spaced outwardly of diverging planes substantially coinciding with said longitudinal partition panels, said discrete posts including lock nose portions extending into said apertures of said transverse partition panels for maintaining said discrete posts at a greater span at said transverse partition panels than the maximum span of said divergent planes.

14. In a blank for a one-piece carton, including a lock panel, cover panel, a back panel, a first bottom panel, a pair of longitudinal partition panels, a second bottom panel, a front panel, a transverse partition panel, and a glue flap panel, hinge forming means connecting said panels, said longitudinal partition panels including support feet forming portions extending into said bottom panels, fold lines extending into said support-feet forming portions for providing a contour to said support feet in an erected carton, said transverse partition panel including full end cell transverse partition panels and an intermediate adjacent half cell partition panel, said longitudinal partition panels being connected to each other on an interrupted fold line, said fold lines extending into said support-feet forming portions substantially communicating with cut lines forming pairs of mirror image central partition panel portions, said central partition panel portions including cut lines colinear with said interrupted fold line and opening toward said cut lines forming said mirror image central partition panel portions for forming the upper ends of a contoured support post which are substantially coplanar with the upper edge of said longitudinal partition of an erected carton.

15. The blank structure of claim 14, in which said central partition panels include cut-out portions intermediate of said interrupted fold line and extending thereacross and terminating at said cut lines forming the mirror image central partition panel portions.

16. The blank structure of claim 14 in which each bottom panel includes pairs of slot portions disposed in spaced relation from the interrupted fold line between said central partition panel portions, said pairs of slot portions being disposed adjacent to one edge and intermediate portion of said blank, said full end cell, transverse partition panels including lock nose structure for engaging in said pairs of slots when the carton is erected, the distance between the innermost ends of said pairs of slots adjacent said blank edge being greater than the corresponding distance between said pair of slots intermediate of said blank whereby the side walls of the erected carton will converge toward the end of the carton when the carton is erected from said blank.

17. In a carton erected from a single blank and comprising a plurality of cells, opposed front and rear walls, transverse partition panels, bottom walls and a longitudinally extending central partition disposed generally parallel between said front and rear walls, said central partition comprising cell-forming portions including downwardly diverging panels including lower foot portions having an edge substantially coincident with the lowermost margins of said front and rear walls, said bottom walls extending inwardly and upwardly from the lowermost edges of said front and rear walls and being joined to intermediate portions of said central partition panels on spaced fold lines disposed below the upper edges of the said central partition panels, said downwardly diverging panels comprising longitudinally spaced panel portions formed by vertical slots terminating above the fold lines between said bottom walls and said diverging partition panels, said transverse partition panels extending through said upwardly opening slots, said diverging partition panels including pairs of free margins on opposite sides of said transverse partition panels, said transverse partition panels including intermediate, depending abutment portions engaging opposed inner surfaces of said diverging central partition panels and orienting the central partition panels into angular relation.

18. In a carton erected from a single blank and comprising a plurality of cells, opposed front and rear walls, transverse partition panels, bottom walls and a longitudinally extending central partition disposed generally parallel between said front and rear walls, said central partition comprising cell-forming portions including downwardly diverging panels including lower foot portions having an edge substantially coincident with the lowermost margins of said front and rear walls, said bottom walls extending inwardly and upwardly from the lowermost edges of said front and rear walls and being joined to intermediate portions of said central partition panels on spaced fold lines disposed below the upper edges of the said central partition panels, said downwardly diverging panels comprising longitudinally spaced panel portions formed by vertical slots terminating above the fold lines between said bottom walls and said diverging partition panels, said transverse partition panels extending through said upwardly opening slots, said diverging partition panels including pairs of free margins on opposite sides of said transverse partition panels, said separated panel portions of said diverging panels including a lock nose portion at said vertical slots, said transverse partition panels including an aperture in substantial alignment with said longitudinal partition panels and receiving said abutment nose portions therethrough.

19. In a carton erected from a single blank and comprising a plurality of cells, opposed front and rear walls, transverse partition panels, bottom walls and a longitudinally extending central partition disposed generally parallel between said front and rear walls, said central partition comprising cell-forming portions including

5 downwardly diverging panels including lower foot portions having an edge substantially coincident with the lowermost margins of said front and rear walls, said bottom walls extending inwardly and upwardly from the lowermost edges of said front and rear walls and being joined to intermediate portions of said central partition panels on spaced fold lines disposed below the upper edges of the said central partition panels, said downwardly diverging panels comprising longitudinally spaced panel portions formed by vertical slots terminating above the fold lines between said bottom walls and said diverging partition panels, said transverse partition panels extending through said upwardly opening slots, said diverging partition panels including pairs of free margins on opposite sides of said transverse partition panels, the transverse width of said carton between said front and rear walls at the end of said carton being greater than the transverse central width at a portion spaced inwardly of the outer ends of said carton, said carton tapering from the transverse central portion thereof toward said outer ends.
